UNITED STATES PATENT OFFICE

RALEIGH J. HIMMELRIGHT, OF NEW ROCHELLE, NEW YORK, ASSIGNOR TO GENERAL REFRactories COMPANY, OF PHILADELPHIA, PENNSYLVANIA, A CORPORATION OF PENNSYLVANIA

FIRE BOX CONSTRUCTION

Application filed March 21, 1928, Serial No. 263,370. Renewed March 6, 1931.

My invention relates to locomotive fire boxes and particularly to an improvement in the thrust block employed at the intersection of vertical and inclined baffle walls in the fire box.

It is customary in engines of certain types to install and maintain a vertical wall projecting across the fire box and extending upwardly to the arch tubes, the latter supporting an inclined horizontal baffle, both of said walls being composed of individual bricks laid in place. It is also customary to mount tubes in the vertical wall, the tubes being anchored in a cross member and serving to stiffen and maintain the integrity of the wall.

In previous constructions, a metal cap piece has been employed, resting on the top of the vertical wall and having wings or lateral projections to underlie the tubes, the metal member acting as a thrust block for transmitting the diagonally downwardly directed force of the inclined arch to the arch tubes and vertical wall.

My invention contemplates a thrust block construction having a leg or downwardly projecting lug adapted to enter the upper end of the tube within the vertical wall the block resting upon the top of the vertical wall. In this manner, the thrust of the inclined arch is transmitted directly to the stiffening tubes in the vertical wall.

The invention will be more readily understood by reference to the accompanying drawings, in which—

Fig. 1 is a longitudinal vertical section through a locomotive fire box constructed in accordance with my invention;

Fig. 2 is an enlarged sectional elevation of a fragment of the construction shown in Fig. 1;

Fig. 3 is a rear view of the thrust block;

Fig. 4 is a sectional view on the line 4—4 of Fig. 3, and

Fig. 5 is a top plan view of the block.

In the drawings, I have illustrated a conventional fire box having a grate 10, arch tubes 11 extending from the throat sheet to the door sheet, and a cast steel cross bearer 12 extending between and permanently secured to the mud rings of the boiler.

A vertical wall 13 of the Gaines type is mounted on the cross bearer, the bricks composing the wall having vertical openings through which is projected a plurality of hollow pipes 14, the lower ends of which are threaded or otherwise secured in the cross bearer, the tubes terminating short of the top surface of the wall.

An inclined horizontal arch 15 is rested on the arch tubes and at the intersection of the vertical and horizontal walls I provide thrust bricks 16 located between the arch tubes and shaped to fit a metal thrust block which will now be described. The block comprises a body of cast metal having a vertical wall 17 which is thickened toward its lower end to provide a base portion 18. Projecting downwardly from the lower surface of the base is a leg 19 of generally circular form in cross section and gradually tapered at its extremity, the taper being formed in two directions as best shown in Figs. 2 and 3. At a point mid-way of the length of the leg I provide a fin 20 and at the lower extremity on the opposite side of the leg I provide a similar fin 21, both fins being integral and of generally pointed shape in cross section.

The leg is intended to be projected into the upper end of a stiffening tube 14 as shown. However, due to some circumstances that cannot always be foreseen, the tubes frequently vary in their inside diameters and the provision of the fins adapts the block to be readily inserted notwithstanding some such variations. If the tube is too small, the area of the fins can readily be reduced by an emery wheel or heavy file without unnecessary delay, and the block may be fitted regardless of small variations in the size of the tubes.

It will be noted that the heavy casting is covered at its top and forward side by the refractory brick 16 being exposed to the action of fire only on its back side. The substantial character of the block and its location in the fire box insures relatively long life. The design is such that the thrust of the arch 15 is transmitted directly to the vertical wall through the stiffening tubes 14.

without any substantial assistance from the arch tubes 11.

Obviously the construction is capable of some modifications, and I do not wish to be limited except as indicated in the appended claims.

I claim:

1. In a locomotive firebox, the combination with arch tubes of intersecting vertical and 10 inclined firebrick walls the latter supported on said arch tubes, hollow metallic stiffening members projecting upwardly within said vertical wall, and a metal abutment block mounted on said vertical wall and having a 15 projection on its lower side adapted to telescope within one of said hollow stiffening members, said block being adapted to receive the thrust of said inclined arch and to transmit said thrust to the vertical wall and stiffening members.

2. The combination with a firebox having arch tubes of a transverse vertical wall having vertical tubes imbedded therein at spaced intervals, an inclined horizontal arch supported on the arch tubes and terminating at 25 the top of said vertical wall and metal thrust blocks resting on said vertical wall and each having a depending leg adapted to fit within a vertical tube in said wall, said block receiving the forward and downward thrust of said inclined arch and transmitting it to 30 said vertical wall and the tubes therein.

3. A thrust block for use at the intersection of vertical and inclined baffles consisting of a body of metal having a relatively broad seat to rest upon the top of the vertical baffle said body being arranged to receive the diagonally exerted thrust of the inclined baffle, and a leg, substantially circular in 40 cross section, integral with and perpendicular to the surface of said seat and adapted to fit within a metal tube within said vertical baffle, said leg being of materially less diameter than the internal diameter of the tube 45 and having a lateral fin near its lower extremity.

In testimony whereof I have affixed my signature.

RALEIGH J. HIMMELRIGHT.
